Primary Examiner — Catherine Ho(74) Attorney, Agent, or Firm — Leydig, Voit & Mayer, Ltd.CLAIM

The ornamental design for a label for food packing, as shown and described.

DESCRIPTION

The patent or application file contains at least one drawing executed in color. Copies of this patent or patent application publication with color drawing(s) will be provided by the Office upon request and payment of the necessary fee. The FIGURE is a front view of a label for food packing showing my new design.
